UNITED STATES PATENT OFFICE.

EDWIN W. LUCE, OF MEADVILLE, PENNSYLVANIA.

OIL-CAN AND FILLER.

SPECIFICATION forming part of Letters Patent No. 515,124, dated February 20, 1894.

Application filed July 22, 1893. Serial No. 481,177. (No model.)

To all whom it may concern:

Be it known that I, EDWIN W. LUCE, a citizen of the United States, residing at Meadville, in the county of Crawford and State of Pennsylvania, have invented certain new and useful Improvements in Oil-Cans and Fillers; and I do hereby declare the following to be a full, clear, and exact description of the invention, such as will enable others skilled in the art to which it appertains to make and use the same.

In a patent granted to me February 4, 1890, No. 420,812, I have shown, described and claimed an oil can or other fluid reservoir provided with a pump for discharging the contents of the vessel, the pump being constructed and arranged to prevent the running over of the lamp or other receptacle to be filled by having the pipe which supplies air to the pump barrel arranged to have its outer end dip into the receiving vessel so that when the fluid rises in the receptacle to the height of the end of the air pipe it will be drawn back into the pump and reservoir through said pipe, thus effectually preventing the overflowing of the same.

The present invention has for its object to provide an improved form of pump for use in connection with the above apparatus; also to adapt the pump for use in filling the reservoir itself, or for emptying the contents of lamps and other receptacles into the said reservoir.

The invention is illustrated in the accompanying drawings forming part of this specification.

Figure 1 is a top plan view of my improved oil can and filler. Fig. 2 is a vertical section on the line 2—2, Fig. 1. Fig. 3 is a similar section on the line 3—3, Fig. 1; and Fig. 4 a detail perspective view of the can spout and its several connections.

Similar letters indicate like parts throughout the different views.

Referring to the drawings, A indicates a can or reservoir for oil or other liquid in the top of which is secured a pump barrel or cylinder B, in which works a solid piston C, having rigidly secured thereto a piston rod c, bent 50 at a right angle at its upper end, as at c', and engaging an eye d carried by a pivoted hand-actuated lever D which is pivoted at its front

end to a standard d' and plays in a guide d² mounted on the head of the can. In the bottom of the pump-cylinder B a valve chamber 55 E is formed, and in this chamber a ball or other suitable valve e is seated, said valve normally closing communication between the reservoir and the pump barrel by gravity. Depending from the bottom of the pump-cylinder and extending nearly to the bottom of the can is a pipe e' through which the fluid is drawn up into the pump by the action of the piston. The pump-cylinder B is provided at or near its opposite ends with valve chambers 65 F, F', the ports of which are normally closed by ball or other suitable valves f, f', and said valve chambers are connected by means of tubes or pipes f², f³, with a chest G, secured in fixed position to the top of the can. Said 70 chest is provided with ports g, g', which are respectively in communication with the tubes or pipes f², f³. H indicates a movable chest similar to the chest G and provided with ports h, h', with which ports spouts h², h³ communicate. The chests G, H, have flat faces where they come together and are provided with a central aperture h⁴ through which passes a bolt h⁵, by means of which said chests are united in such manner that the chest H may be 80 relatively turned to the chest G so as to cause the ports leading to the interior of the reservoir to register with those leading to the spouts h², h³. The spouts h², h³, may be made entirely separate and distinct throughout their 85 length, but I prefer to have their ends terminate in a single spout divided into two channels by a separating partition h⁶, as shown in Fig. 2, and in either case the ends will be bent downward so as to facilitate their introduction into the mouth or opening of a lamp or other receptacle. The upper end of the cylinder B is also provided with an outlet pipe I communicating with the interior of the can and provided with a normally closed valve i 90 opening outward relatively to the pump cylinder and held in closed position by gravity. This valve permits the fluid which is drawn into the cylinder from the receiving vessel through the pipe f² to be forced back into the 95 body of the reservoir by the upward movement of the piston.

As thus far described, the purpose and function of the pump are the same as that shown

in my former patent. The construction and method of operation are, however, different, the principal difference being that the pump shown herein is a combined lift and force 5 pump, raising the fluid from the reservoir into the cylinder and forcing it therefrom into the receiving vessel through the discharge pipe, whereas the apparatus illustrated in the old patent operated to expel the fluid by the 10 pressure of air forced into the reservoir above the contents by the pump.

For the purpose of adapting the pump for use in filling the reservoir itself, or for emptying the contents of lamps and other vessels, 15 I provide the following arrangement: At or near the bottom of the pump barrel one end of an open tube J connects. The opposite end of this tube extends upwardly and preferably to the head of the can or reservoir. 20 The tube is provided with apertures j, which afford communication between the interior of the vessel and the bottom of the pump-cylinder. Fitted in said tube is a tightly fitting solid plunger K provided with a rod k extending up through the tube above the top 25 of the can, the purpose of this plunger being to open or close communication between the cylinder and the interior of the reservoir through the pipe J.

30 The operation of the device is as follows: When a lamp or other vessel is to be filled, it is placed under the spout so that the latter projects down into the vessel to the level at which it is desired to fill the same. The piston C being at the bottom of the pump-cylinder and the plunger K being fixed in the pipe J below the opening j as shown in Fig. 2, upon raising the piston by means of its operating handle D the air above the piston will be forced 35 out through the pipe I, opening the valve i and passing into the interior of the reservoir A. As the piston rises, it will also lift up the fluid through the pipe e'. During the upward movement of the piston C, the valves f, f', remain 40 closed. The piston is now at the upper end of the cylinder, and, as it descends, the valves i and e close, shutting off communication between the cylinder and the interior of the reservoir. The valves f and f' meanwhile open, 45 the former permitting air to enter above the piston through the spout h² and pipe f², and the latter allowing the fluid beneath the piston to be forced out through the pipe f³ and spout h³ into the receiving vessel. This 50 operation is repeated until the oil in the lamp or other receiving vessel rises and closes the lower end of the spout h³ against the ingress of air to the cylinder, when the continued operation of the pump merely pumps in and out 55 of the lamp equal volumes at each stroke. To prevent the entrance of solid matter into the pump cylinder through the air pipe h², I cover its end with wire gauze, or similar material, as shown in Fig. 2.

60 For the purpose of filling the reservoir itself, or emptying a lamp or other vessel containing fluid, the plunger K is adjusted in the

tube J to a point above the apertures j, and the pump piston is operated in the same manner as before described. It results from this arrangement, that, upon the down stroke, the oil beneath the piston, seeking the path of least resistance, will pass into the tube J and out through the apertures j into the reservoir. As the piston descends again it draws up the 75 oil through the spout h² into the cylinder above the piston, the ends of the spout being dipped down to the bottom of the lamp. Upon the next upward stroke of the piston the oil above the same is forced out of the 80 cylinder into the reservoir through the outlet I. During the upward stroke of the piston, air from the interior of the reservoir freely enters the cylinder through the tube J and no fluid is drawn up through the pipe e'. 85

I wish it to be understood that I do not regard the invention herein as limited to the particular form of pump, or the specific details of construction or arrangement of the apparatus, as many variations of the same 90 are obviously within the spirit and scope of the same.

Having thus described the invention, what I claim is—

1. The combination with a fluid reservoir, 95 of a pump for discharging the contents thereof into a receiving vessel, said pump comprising a cylinder, an inlet pipe extending down into the reservoir, a discharge pipe leading to the receiving vessel, an air inlet pipe leading 100 from the receiving vessel back to the pump cylinder, and an air outlet between the cylinder and the interior of the reservoir, substantially as described.

2. The combination with a fluid reservoir, 105 of a pump for discharging the contents thereof into a receiving vessel, said pump comprising a cylinder, a solid piston, an inlet pipe connected with the cylinder and extending down into the reservoir, a discharge pipe leading 110 from the cylinder on one side of the piston to the receiving vessel, an air inlet pipe leading back from the receiving vessel to the cylinder on the other side of the piston, and an air outlet from the cylinder to the reservoir 115 on the same side of the piston as the air inlet, substantially as described.

3. The combination with a fluid reservoir, 120 of a pump cylinder inclosed within the reservoir, a solid piston working in said cylinder, an inlet pipe leading from outside the reservoir into the pump cylinder, said pipe containing a valve opening inwardly toward the cylinder, and an outlet pipe leading from the cylinder to the interior of the reservoir, said 125 outlet pipe containing a valve opening outwardly from the cylinder; substantially as described.

4. The combination with a fluid reservoir, 130 of a pump cylinder, an inlet pipe extending from the cylinder down into the reservoir, a discharge pipe leading from the cylinder outside of the reservoir, an inlet pipe leading from outside the reservoir into the cylinder,

an outlet between the cylinder and the interior of the reservoir, a separate pipe forming communication between the cylinder and the interior of the reservoir, and a valve operable from the outside of the reservoir for controlling communication between the cylinder and reservoir through said pipe; substantially as described.

5 5. The combination with a fluid reservoir, of a pump cylinder inclosed within the reservoir, a communication between the cylinder and reservoir controlled by a valve opening into the cylinder, a discharge pipe leading outside of the reservoir and containing a valve 10 opening outwardly from the cylinder, an inlet pipe leading from outside the reservoir back to the cylinder and containing a valve opening inwardly toward the latter, and an outlet between the cylinder and the reservoir, said 15 outlet being controlled by a valve opening outwardly from the cylinder; substantially as described.

6. The combination with a fluid reservoir, of a pump cylinder inclosed within the same,

a solid piston working in the cylinder, a communication between the cylinder and the reservoir controlled by a normally closed valve opening into the cylinder, a discharge pipe leading from the cylinder on one side of the piston to the outside of the reservoir and controlled by a normally closed valve opening away from the cylinder, an inlet pipe leading from outside the reservoir back to the cylinder on the other side of the piston and controlled by a normally closed valve opening 35 toward the latter, and an outlet from the cylinder on the same side of the piston as the inlet from outside the reservoir, said outlet being controlled by a normally closed valve opening outwardly from the cylinder; substantially as described.

In testimony whereof I affix my signature in presence of two witnesses.

EDWIN W. LUCE.
